ADHESIVE APPLYING ROLLER MECHANISM
FOR LABEL PASTING MACHINES

Frank Elsner, Hanover, Pa.

Application May 25, 1949, Serial No. 95,246

6 Claims. (Cl. 91—50)

1

This invention relates generally to the class of label pasting and is directed particularly to improvements in adhesive transfer rollers.

The adhesive pick-up and transfer mechanism of the present invention is designed primarily for use in association with label applying machines of the type wherein a label pick-up member is supported to move across the paste transfer roll to draw the label thereover and it is a principal object of the present invention to provide a paste pick-up and transfer mechanism which is designed in a novel manner whereby the mechanism will be maintained at the proper elevation for movement of a label over the transfer roll and may be lowered to prevent contact of the label pick-up member with the transfer roll upon its return movement.

Another object of the invention is to provide a novel paste pick-up and transfer mechanism comprising a lower pick-up roll and upper transfer roll, wherein the two rolls are both supported as a unit upon a pair of bracket members which are in turn connected with and supported by vertical posts which are adapted to have vertical movement for elevating and lowering the rollers for the purpose above set forth.

Another object of the invention is to provide in an apparatus of the character stated novel means whereby the rolls may be leveled as a unit to facilitate the proper alignment of the surface of the transfer roll with the surface of a label moved thereacross by the label pick-up and transfer mechanism.

Still another object of the invention is to provide in an apparatus of the character stated, a novel means for adjusting the transfer roll with respect to the surface of the pick-up roll.

A still further object of the invention is to provide in an apparatus of the character stated, a novel means for draining off from the pick-up roll excess of adhesive by novel formation of the ends of the pick-up roll whereby the adhesive will be prevented from accumulating at the ends of the transfer roll.

Other objects and advantages of the present invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawing:

Figure 1 is a view partly in vertical section and partly in end elevation of an adhesive transfer roller mechanism constructed in accordance with an embodiment of the present invention.

Figure 2 is a view of the same in rear elevation.

2

Referring now more particularly to the drawing the numeral 10 designates a pair of spaced upright standards each of which has an inturned guide arm 11 at its upper end. These guide arms, as shown, are in aligned relation transversely of the apparatus and each has formed therethrough a vertical guide bearing or opening 12.

At a suitable elevation below the arms 11 is supported a floor plate for platform 13 which has therethrough two bossed guide openings 14 each of which is in alignment with an opening 12.

Extending upwardly through each two vertically spaced aligned openings 12 and 14 is a rod member which forms one side of an upright substantially U-shaped frame which is generally designated 16 and which has at its lower part the cross bar 17 which connects the lower ends of the rods 15 together below the platform 13 as shown. This cross bar 17 has pivotally connected therewith as at 18, an end of a pitman 19 by means of which vertical movement is transmitted to the frame 16 from a suitable mechanism (not shown) which may be in the form of a rotating cam opposed by a spring, by means of one of which upward movement is given to the frame while the other one effects reverse or downward movement thereof.

Mounted upon the table or platform 13 between the vertical bars 15 is a water bath heated paste receptacle 20 which has beneath it the water bath receptacle 21, the two receptacles being connected as a unit, with the paste receptacle 20 fitting into the water bath receptacle 21 as shown in Figure 2 and both mounted upon suitable supporting legs 22.

Supported upon each rod 15 is a bracket unit which is generally designated 23 and which comprises a relatively long vertically disposed sleeve 24 through which the rod 15 passes and a bearing block 25 integral with the sleeve as shown in Figure 1 and extending therefrom at a slight downward inclination as shown. The bearing block 25 has formed therein from the underside a recess 26 which is closed at its lower end by the cap 27. This cap includes a central spring cup 28 in which is housed a coil spring 29.

Within the recess or guide 26 is a bearing body 30 which has the central opening 31 in which is received an end of a trunnion 32 connected with or forming a part of an end of the pick-up roll 33. The sides of the guide recesses 26 are, of course, open and the bearing 30 is of greater width than the block 25 and is provided at the two sides with flanges 30a which engage the adjacent side faces of the block 25 to maintain the bearing 30 in proper position. The spring 29 engages the underside of the bearing 30 and constantly urges the same upwardly.

The roller 33 which extends down into the paste receptacle 20 is of substantial length as shown in Figure 2 and at each end it is beveled off or

chamfered to form a drainage shoulder for the purpose hereinafter set forth.

Below each sleeve 24 the rod 15 carries a sleeve 35 and beneath this is fixed a collar 36 and between the collar 35 and sleeve 36 is a compression spring 37. While the sleeve 35 has been here shown as a separate member from the sleeve 24 it might be formed in one piece therewith if desired.

Fixed to each rod 15 above the sleeve 24 is a fixed internally threaded collar 38 and between this collar and the top of the sleeve 34 is an adjusting nut 39 which rests upon the top of the sleeve 24 and has the reduced cylindrical extension 40 which is externally threaded and threads into the collar 38. By means of this nut 39 a downward thrust may be applied to the sleeve 24 to move the latter against the resistance of the underlying spring 37.

As shown in Figure 2 one of the trunnions 32 of the roller 33 is extended beyond its supporting bearing 30 and carries thereon the large spur gear 41.

Formed integral with each bearing block 25 and extending upwardly from the top thereof is a relatively long guide neck 42 through which is formed a passage 43 and this neck supports at its upper end a bearing head 44 through which the passage 43 continues to open through the top of the head. This bearing head is constructed upon the side away from the rod 15 to form a half section of a bearing 45, the other half section of the bearing being comprised in a bearing plate 46 which is bolted to the side of the head in the manner shown in Figure 1. The bearings 45 have rotatably mounted therein the ends of trunnions 47 carried by the ends of the paste transfer roller 48. One of these trunnions 47, as shown in Figure 2, extends beyond the outer side of its supporting bearing and carries the pinion gear 49 which meshes with the large gear 41. The other trunnion 47 also extends beyond its bearing 45 and carries a sprocket wheel 50 around which is trained a driving chain 51 which is operated from any suitable source of power to impart rotation to the trunnions 47 and through the gears 49 and 51 to the roller 33.

Threaded downwardly into the upper end of the bore 43 is an adjusting screw 52 which carries a knurled head 53 upon its upper end. This screw extends only partway down into the passage 43 as illustrated and below the screw and extending through the lower part of the passage 43 into the bearing guide recess 26 is a stem 54 which rests upon the top of the bearing body 30 and passes through a clearance collar or washer 55 which rests upon the top of the body 30. This collar 55 prevents the bearing body 30 from being forced upwardly beyond a position where the pick-up roller 33 will lightly contact the surface of the transfer roller 48. Normally the adjusting screws 52 will be set so as to force the pick-up roller 33 downwardly to provide a space or clearance between the roller surfaces of very minute width. By this means a layer of adhesive carried by the surface of the pick-up roller 33 will be in part transferred to the surface of the roller 48. The excess adhesive carried by the lower roller will accumulate in the bight between the converging surfaces of the rollers and will be worked laterally toward the ends of the roller 33 and be drained off across the downwardly inclined shoulders 34.

With the two adjusting means described it will be seen that the rollers 33 and 48 may be adjusted relative to one another to increase or decrease the clearance between their surfaces and

also the two rollers may be adjusted as a unit on the vertical rods 15 of the carrying frame whereby to bring about the necessary parallelism between the surface of the transfer roll 48 and the face of the label pick-up or suction head which swings across the top of the roller 48 and which is shown in dotted outline and designated 56.

I claim:

1. An adhesive applying roller mechanism, comprising a receptacle, an upright frame having the receptacle arranged within the outline thereof, means supporting the frame for vertical movement, a pair of parallel rollers supported horizontally one above the other in and by the frame, the lower roller having its lower portion within the receptacle, means for transmitting rotary motion to the rollers from a source, and means for transmitting reciprocating motion to the frame from a power source.

2. A mechanism of the character stated in claim 1, wherein the receptacle is stationary with respect to the frame and the rollers carried thereby.

3. An adhesive applying roller mechanism of the character described in claim 1, wherein the rollers are adjustable as a unit within and with respect to the frame by which they are supported.

4. An adhesive applying roller mechanism, comprising a stationary receptacle, a pair of vertical members between which the receptacle is positioned, means supporting said members for unitary up and down movement, a body supported upon each of said vertical members, means for vertically adjusting the bodies upon the members, a lower pair of bearings each carried by one of said bodies, a roller supported between the lower pair of bearings and having its lower portion disposed within the receptacle, an upper pair of bearings each supported by a body, a roller supported between the upper pair of bearings with its periphery in close proximity to the periphery of the lower roller, and means for rotating said rollers.

5. An adhesive applying roller mechanism, comprising an upright frame including two spaced parallel upright members, means supporting the frame for vertical reciprocation, a sleeve mounted upon each of said upright members for vertical movement, a bearing block carried by each sleeve, a bearing supported in each bearing block, a roller disposed between the bearing blocks and having trunnions each rotatably supported in a bearing, a bearing supported above and upon the top of each bearing block, an adhesive transfer roller disposed between the second two bearings and having end trunnions each rotatably mounted in one of the second mentioned bearings, means for adjusting the first mentioned bearings in the bearing blocks for adjusting the spacing between the rollers, and means for applying adhesive to the first mentioned roller.

6. An adhesive applying roller mechanism of the character stated in claim 5, wherein the said means for adjusting the first mentioned bearings comprises a spring supported upon the underside of each bearing block and pressing upwardly against the underside of the adjacent bearing, and a screw actuated pin extending downwardly through the top of each bearing block and engaging the top of the adjacent bearing to effect the downward movement of the bearing against the upward thrust of the adjacent spring.

FRANK ELSNER.
